(57) CLAIM

The ornamental design for an audio and charging station for a handheld electronic device, as shown and described.

DESCRIPTION

FIG. 1 is a perspective view of an audio and charging station for a handheld electronic device showing my new design; FIG. 2 is a front elevational view, the rear elevational view being identical;

FIG. 3 is a top plan view thereof;

FIG. 4 is a side elevational view, the opposite side elevational being identical; and,

FIG. 5 is a perspective view shown with a handheld electronic device in broken lines.

The broken line showings of the rectangle in FIG. 1, and the handheld electronic device in FIG. 5 are for illustrative purposes only and form no part of the claimed design.

1 Claim, 4 Drawing Sheets

FIG. 1

FIG. 4
